UNITED STATES PATENT OFFICE

99,370

DESIGN FOR A SHOE OR SIMILAR ARTICLE

Edmond Saugues, Woodhaven, N. Y.

Application December 28, 1935, Serial No. 60,320

Term of patent 3½ years

To all whom it may concern:

Be it known that I, Edmond Saugues, a citizen of the United States of America, residing in Woodhaven, L. I., county of Queens, and State of New York, have invented a new, original, and ornamental Design for a Shoe or Similar Article, of which the following is a specification, reference being had to the accompanying drawing, forming part thereof,

Fig. 1 is a bottom plan view of a shoe showing my new design, the shape of the shoe being conventional, and

Fig. 2 is a bottom perspective view of the same.

The breast of the heel follows through the shank verging into a point on the sole.

I claim:

The ornamental design for a shoe or similar article substantially as shown and described.

EDMOND SAUGUES.
